PAPER DISPENSER

Donald McDonald, Dayton, and Paul W. Frobe,
Cincinnati, Ohio

Application July 18, 1949, Serial No. 105,310

11 Claims. (Cl. 242—55.5)

1

This invention relates to a paper dispenser and more particularly to a dispenser of the type used in dispensing toilet paper and which automatically dispenses a predetermined quantity of paper in response to actuation of a push button or the like.

Various paper dispensers have been designed from time to time, but each of these have had disadvantages in that they have been hard to refill and have had poorly designed feed mechanisms or have not provided the necessary sanitary features. Dispensers of this type should be foolproof and sturdy as they are commonly used in public places where they receive considerable abuse and where it is important that the main supply of paper be fully enclosed.

It is an object of this invention to provide a paper dispenser in which the user only has access to that portion of the paper which is to be cut off by the user. This object is accomplished by providing a dispenser in which additional paper is exposed only after the user has cut off the desired amount of paper.

More particularly it is an object of this invention to provide a dispenser in which pressure on a spring pressed plunger or the like first severs a predetermined quantity of paper as the plunger is pushed in and then prepares to dispense a new supply of paper as the plunger moves outwardly.

Another object of this invention is to provide a dispenser in which pressure applied by one's arm or the like automatically severs and dispenses a predetermined quantity of paper.

Another object of this invention is to provide a paper dispenser in which standard rolls of paper may be inserted with a minimum amount of inconvenience.

Another object of this invention is to provide a practical dispenser which may be manufactured at a low cost.

Still another object of this invention is to provide a dispenser which is quiet in operation.

Other objects and advantages reside in the construction of parts, the combination thereof and the mode of operation, as will become more apparent from the following description.

In the drawings:

Figure 1 is a vertical sectional view of the device taken substantially on line 1—1 of Figure 2, with parts broken away, so as to expose the paper feeding mechanism;

Figure 2 is a front elevational view with parts broken away;

Figure 3 is a side elevational view with parts broken away; and

2

Figure 4 is a side elevational view showing the dispenser opened up for insertion of a new supply of paper.

For purposes of illustration, the invention has been shown as applied to a toilet paper dispenser, whereas certain features of the invention are equally applicable for use in dispensing other types of paper and various other kinds of paper thin material. Consequently, the term paper as used herein is intended to be given a broad interpretation and to apply to various equivalent kinds of strip material. Likewise, the unit shown is one that is intended to be countersunk into a recess in the wall, whereas it is to be understood that certain aspects of the invention are equally applicable to units which are adapted to be mounted on a flat surface.

Referring now to Figure 1 of the drawings, reference numeral 10 designates a main frame which is adapted to be inserted into a recess in a wall such as the wall 12. The frame 10 includes a rear guard 14 which may be in the form of a strip as shown or it may be in the form of a fully closed casing which is adapted to be countersunk into a recess in a wall in accordance with common practice.

As best shown in Figures 3 and 4, a roll of paper 17 is adapted to be supported on a spindle 16 carried by a movable inner frame member 18 which is hinged to the main frame 10 at 20 and is adapted to swing out from the main frame for refilling as shown. The inner frame member 18 is provided with an arcuate paper guide wall 22 over which the free end of the paper 21 is arranged to pass as shown.

As indicated in Figure 4 of the drawings, the roll of paper is mounted on the spindle 16 with the free end 21 of the paper overlying the arcuate guide wall 22. In refilling the dispenser, the new roll of paper is simply laid in place with the free end hanging down as shown. The paper feeding and cutting mechanism is carried by the outer movable frame or cover member 24 which is hinged to the main frame 10 at 26. The outer frame or cover member 24 is provided with side flanges 25 which project into the main frame 10. The cover 24 serves to conceal the main supply of paper and serves to both enclose and support the paper feeding and cutting mechanism.

As best shown in Figure 1 of the drawings, the main operator 28 for the paper feeding and cutting mechanism comprises a sheet metal stamping which includes a push button or push bar portion 28 which projects forwardly at the bottom edge of the cover 24. The operator 28 is

hinged to the outer frame or cover 24 by means of the hinge pin 30 which also supports the cam 58 which will be described hereinafter. The portion 28 has a serrated paper cutting edge 32 formed along its bottom edge. The serrated paper cutting edge 32 cooperates with a complementary serrated cutting edge 34 provided at the lower end of the paper guide 22 as shown in Figure 1.

In order to hold the paper during the cutting operation, there has been provided a paper gripping crossbar or brake 36 which is mounted on the lower end of a spring leaf 38 secured to the inner surface of the operator 29. This crossbar moves with the operator 29 and serves to clamp the paper against the serrated cutting edge 34 as pressure is applied to the button or bar 28 so as to firmly grip the paper during the cutting operation, thus serving as a brake. The mechanism for feeding the paper is designed so as to feed a new supply of paper as the operator 29 moves out rather than when the operator moves in as is the usual practice. The main operator 29 is biased into its full line position, as shown in Figures 1 and 3, by suitable spring means such as the blade spring 40 (see Figure 3) which has its upper end welded or otherwise secured to the inner surface of the cover 24 and has its lower end pressing against the inner surface of the operator 29. The paper feeding mechanism comprises an arm or lever 50 which is adapted to rotate or oscillate about a pivot pin 52 which is fixed to the side flange 25 of the cover 24. The outer end of the arm 50 is bent over, as shown in Figure 2, and pivotally supports an elongated rubber finger or paper feeder 54. The arm 50 carries a roller 56 which cooperates with an operating cam element 58. The cam element 58 is secured to the hinge element 59 which in turn is pivotally supported on the hinge pin 39. The cam element 58 is adapted to be moved from its full line position shown in Figure 1 to the dotted line position by means of the cam element 60 which is secured directly to the operator 29 and which supports a pair of rubber buffers 62 in such a manner that there is a lost motion connection between the cam element 58 and the operator 60. A compression coil spring 61 is arranged as shown for preventing rattling and for urging the operator 29 to move away from the hinge element 59. As pressure is applied on the push bar 28, the element 60 acting through the lower buffer 62 will shove the cam element 58 upwardly so as to move the paper feeding arm 50 from its full line position into its dotted line position. The weight of the depending portion of the finger element 54 plus the weight of the overhanging end 55 of its supporting shaft tend to cause the element 54 to normally hang downwardly as shown in Figure 1. During the first portion of the upward movement of the arm 50, the paper feeding element 54 does not contact the paper whatsoever and when the arm 50 approaches its upper position, the corner of the element 54 lightly rides over the paper without moving the paper. As the element 54 approaches its upper position, the paper clamping crossbar or brake 36 will have moved into paper clamping position and will prevent the paper feeding element 54 from feeding the paper in the wrong direction. However, when pressure on the push bar 28 is released, the spring 40 will begin to return the parts to their full line position and as the parts thus return, the paper gripper 54 will feed a predetermined quantity of paper from the roll 75

17. During the return stroke of the operator 29, the upper buffer 62 will engage the upper edge of the cam element 58 and will initiate its return to its full line position as shown in Figure 1. A spring 64, which has its one end secured to the arm 50 and has its other end secured to the pin 66 carried by the flange 25, serves to operate the arm 50 and the paper gripper 54 in the paper feeding direction. The force 10 of the spring 64 also assists in forcing the cam element 58 to return to its full line position once the roller 56 rides over the peak point on the cam element 58.

15 The relationship between the center of rotation of the arm 50 and the curvature of the paper guiding wall 22 is such that the gripper 54 loses its grip on the paper at the end of the paper feeding movement. By virtue of the above described arrangement, it is obvious that a new 20 supply of paper is fed down as the push bar 28 and operator 29 return to their normal position and that the user can pull out any additional amount of paper he wishes before pressing on the operating bar 28 for severing the paper. The 25 amount of paper automatically fed down by the dispenser is largely determined by the shape and arrangement of the cam element 58 and the design is preferably such that the desired amount of paper is automatically fed down whereby it is not necessary to exert any further 30 pull on the paper.

35 Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and 40 defined in the appended claims.

Having thus described our invention, we claim:

1. In a paper dispenser, a main frame, an inner frame pivotally mounted on said main frame and having means thereon for supporting a roll of paper from which paper is to be dispensed, and 45 a cover for said main frame and cooperating with said main frame to substantially enclose said roll of paper and said inner frame, said cover being hinged to the main frame adjacent the upper edge thereof and adapted to be raised to expose the inner frame, said inner frame being hinged to said main frame adjacent the bottom edge thereof and being adapted to swing outwardly and downwardly so as to be accessible while renewing the supply of paper.

2. In a paper dispenser, a main frame, an inner frame pivotally mounted on said main frame and having means thereon for supporting a roll of paper from which paper is to be dispensed, and 50 a cover for said main frame and cooperating with said main frame to substantially enclose said roll of paper, said cover being hinged to the main frame adjacent the upper edge thereof and adapted to be raised to expose the inner frame, said inner frame being hinged to said main frame adjacent the bottom edge thereof and being adapted to swing outwardly and downwardly so as to be accessible while renewing the supply of paper, said inner frame having a side wall on 55 which a paper roll supporting spindle is carried and an arcuate paper guide wall partially surrounding the roll of paper and over which the paper to be dispensed is adapted to pass, said 60 guide wall terminating in a cutting edge.

3. In a paper dispenser, a main frame, an inner frame pivotally mounted on said main frame and having means thereon for supporting a roll of paper from which paper is to be dispensed, a cover for said main frame and cooperating with said main frame to substantially enclose said roll of paper, said cover being hinged to the main frame adjacent the upper edge thereof and adapted to be raised to expose the inner frame, said inner frame being hinged to said main frame adjacent the bottom edge thereof and being adapted to swing outwardly and downwardly so as to be accessible while renewing the supply of paper, said inner frame comprising a side wall having a paper roll supporting spindle carried thereby and an arcuate guide wall over which the paper to be dispensed is adapted to pass, said arcuate guide wall terminating in a serrated cutting edge, and means having a complementary serrated cutting edge, said last named means being pivotally supported on said cover.

4. In a dispenser for use in dispensing strip material, a main frame, means carried by said main frame for supporting a quantity of strip material, a cover cooperating with said main frame for enclosing said supply of strip material, a lever pivotally carried by said cover and including a projecting push button adjacent its one end, means for biasing said push button outwardly, means for severing said strip material including a cutting element carried by said push button and operable to cut the strip material upon inward movement of said button, strip feeding means operable in response to outward movement of said push button for feeding a predetermined new supply of said strip material, said cover having a bottom outlet through which said strip material is to be dispensed, and means carried by said push button for gripping said strip material during the cutting operation.

5. In a paper dispenser, a main frame, means for supporting a roll of paper within said main frame, a closure member cooperating with said main frame for enclosing said roll of paper, paper feeding means carried by said closure member, paper cutting means carried by said closure member, and a common operator supported on said closure member for operating said paper feeding means and said paper cutting means, said paper feeding means comprising a pivoted lever having a cam follower mounted thereon, a cam element pivotally supported by said closure member and adapted to actuate said cam follower so as to cause oscillation of said lever, and means operated by said operator for oscillating said cam element, said last named means having a lost motion connection with said cam element.

6. In a paper dispenser, a main frame, flange means for positioning said frame in a fixed position in an aperture in a wall, said frame having an opening at the front thereof which is in alignment with said flange means, an inner housing pivotally secured to the lower edge of said main frame and swingable into and out of said opening in the main frame, a roll supporting spindle carried by said inner housing, cover means for said opening and for enclosing said inner frame, said last named means comprising a cover element which is hinged at its upper edge to said flange means and which is adapted to be swung out of the path of said roll supporting frame so as to expose said supporting spindle.

7. In a dispenser for use in dispensing strip material from a roll, means for supporting said strip material including a circular shield over-

lying said roll, means for guiding said material over said circular shield, means cooperating with said strip as it passes over said shield for feeding a predetermined quantity of said material, said feeding means including a gripper operable to move in two directions and being operable to frictionally engage the material in its one direction of movement, operating mechanism for said feeding means, and cutting means for cutting said material operated in response to movement of said operating mechanism in the one direction, said mechanism serving to cause said cutting means to sever said strip in the one direction of movement of said operator and serving to operate said strip feeding means in the other direction of movement of said operator.

8. In a dispenser for use in dispensing toilet paper, a main frame, means carried by said main frame for supporting a roll of toilet paper, a cover cooperating with said main frame for enclosing said paper, a lever pivotally carried by said cover and including a projecting push button at its one end, means for biasing said push button horizontally, said push button comprising an elongated one-piece bar-like element formed of stamped sheet metal and terminating in a serrated cutting edge, and paper feeding means operable in response to outward movement of said push button for feeding a predetermined length of the paper.

9. In a paper dispenser, a main frame, means for supporting a roll of paper within said main frame, a closure member pivotally mounted on said main frame and cooperating with said main frame in the one relative position thereof for enclosing said roll of paper, paper feeding means carried by said closure member, paper cutting means carried by said closure member, and a common operator supported on said closure member for operating said paper feeding means and said paper cutting means.

10. Means for dispensing paper from a roll comprising in combination, a stationary frame, a cover hinged to said frame, a roll supporting frame pivotally supported on said stationary frame and including an arcuate guide surface over which the paper to be dispensed travels, a paper feeding means including a lever, means for pivotally supporting said lever on said cover, a paper feeding finger pivotally carried at the end of said lever for feeding the paper over said guide surface, and a counterbalance weight for urging said finger out of engagement with said paper in the one position of said lever and for urging said finger into engagement with said paper in another position of said lever.

11. In a dispenser for use in dispensing strip material, a main frame, means carried by said main frame for supporting a quantity of strip material, a cover cooperating with said main frame for enclosing said supply of strip material, a lever pivotally carried by said cover and including a projecting push button, means for biasing said push button horizontally outwardly, means for severing said strip material including a cutting element formed integrally with the lower edge of said push button and operable to cut the strip material, and strip feeding means operable in response to outward movement of said push button for feeding a predetermined length of said strip material.
